FIG. 2.

FIG. 3.

INVENTOR.

DONALD J. CAMPBELL.

BY *Frank E. Liverance, Jr.*

ATTORNEY.

UNITED STATES PATENT OFFICE.

DONALD J. CAMPBELL, OF MUSKEGON HEIGHTS, MICHIGAN.

MOLD-DRAWING APPARATUS.

Application filed February 10, 1921, Serial No. 443,740. Renewed November 2, 1923.

To all whom it may concern:

Be it known that I, DONALD J. CAMPBELL, a citizen of the United States of America, residing at Muskegon Heights, in the county of Muskegon and State of Michigan, have invented certain new and useful Improvements in Mold-Drawing Apparatus; and I do hereby declare the following to be a full, clear, and exact description of the invention, such as will enable others skilled in the art to which it appertains to make and use the same.

This invention relates to a mechanism adapted for use in levelling and drawing one part of a mold from a box in which the mold is made. More specifically, with this invention, it is contemplated that after a mold has been formed in the box, said box is to be moved over the mechanism of my invention which may be moved upwardly to engage against the under side of the mold and which contains structure whereby the upper or table portion of the mechanism may automatically conform to the under surface of the mold plate. Then said table is locked against movement and afterward lowered to a lower plane, the mold which has been made, drawing from the box and disassociating therefrom so as to be removed for further use in the completed mold. It is a primary object and purpose of the present invention to make a mechanism of this character with which molds may be quickly and easily withdrawn from the boxes in which made, without injury to the mold. A further object of the invention is to construct the mechanism so that it can be very expeditiously operated, and with a minimum of expenditure of energy, the same being hand operated and repeatedly so that ease of operation is a very valuable feature. A still further object is to construct the mechanism simply and economically, and at the same time insure accuracy in operation and durability in service. These and various other valuable features of the invention will appear as understanding thereof is had from the following description, taken in connection with the accompanying drawings, in which,

Fig. 1 is a side elevation of the mechanism of my invention, showing the same in lower position after a mold has been drawn from its forming box.

Fig. 2 is a vertical section through said levelling and drawing mechanism.

Fig. 3 is a horizontal section on the plane of line 3—3, of Fig. 2 and looking in a downward direction.

Fig. 4 is a like section on line 4—4 of Fig. 2.

Fig. 5 is a perspective view of the cam locking member for the mold carrying table, and

Fig. 6 is a vertical section through the cap which covers said cam locking device.

Like reference characters refer to like parts in the different figures of the drawings.

In the construction shown, a vertical supporting post 1 is used, this being one of the posts forming a part of a compressed air mold ramming machine which is the subject matter of another application for patent Serial Number 443,739, filed Feb. 10, 1921. The post, at its lower end has connection with a suitable base member 2 and on the post directly above said base member a sleeve 3 is mounted which may be turned to different positions, as desired, and secured in any position to which adjusted by a suitable clamping means, illustrated at 4. An arm 5 projects outwardly and slightly downwardly from sleeve 3, being formed integral therewith and at its outer end carries a second vertically positioned sleeve 6 which, at its upper outer portion has a plate-like projection 7 forming one side of a housing which is completed by a plate 7^a paralleling part 7 and attached thereto in spaced relation therefrom. Within the housing thus made a disk 8 is rotatably mounted to turn about a horizontal axis and at the inner sides of which a series of gear teeth 9 are cut or otherwise formed.

A handle 10 is connected at one end to the disk 8 and passes outwardly therefrom through a slot 11 formed in the outer portion of the housing, the same being equipped at its free end with the usual crank handle 12. Member 10 is slotted in one side forming a guide in which a latch bar 13 is slidably mounted, the same being equipped at its outer end with an out-turned handle 14 which parallels part 12 and is normally forced away therefrom by a compression spring 15 interposed between the same. A ratchet bar 16 provided with a consecutive series of ratchet teeth 17 at its outer side is located in the slot in the housing alongside of the handle 10 in position such that the latch bar 13 at its inner end is normally

forced into engagement between two of the teeth 17.

A post 18 is located in the sleeve 6 and at one side is formed with a series of rack teeth 19 which are in engagement with the teeth 9 on disk 8, it being evident that the post may be raised or lowered by proper operation of the disk 8. A vertical key 20 is fixed in the sleeve 6 and enters a vertical key way 21 in the post 18, serving to keep the post from rotation.

At its upper end, post 18 is enlarged and formed with a socket, as indicated at 22 for the reception of the lower portion of a ball 23, integral with which a short post 24 is formed which extends upwardly and to which at its upper end a table 25 is attached. A cap 26 is placed against the upper end of post 18 and over the ball 23, the post 24 passing upwardly through an opening in the upper side of the cap, said cap being formed with an outwardly extending flange 27 at its lower edges which rests against a flange 22^a formed integral with the socket member 22, screws 28 connecting the same together. The under side of the top of the cap is formed with an inclined cam surface 29 as best shown in Fig. 6.

A ring 31 is located under the cap and between it and the ball 23. On its upper side it is formed with an inclined cam surface 32, the ends of which lie one above the other and are joined at a vertical shoulder as indicated at 32^a. The under side of the ring around the opening therein is formed with a recess 33 shaped to fit the upper portion of the ball. An operating handle 34 extends from the ring through a slot 30 in a side of cap 26, it being evident that by turning the ring through operation of the handle, it may be clamped against the upper side of the ball 23, thereby locking the ball and attached table 25 against movement.

A sleeve 35 is rotatably mounted on the post 1 above sleeve 3 from which a supporting arm 36 projects, the same being divided at its outer portion to make a fork between the parts of which the mold box 37 is rotatably mounted, trunnions 38 on the box seating in properly formed socket bearings 39 at the ends of the forks. In filling the mold, a plate 40 of special design, the construction of which forms the subject matter of a separate application for patent Serial Number 454,192, filed March 21, 1921, is clamped against the upper side of the box 37, which is turned over from the position shown in Fig. 1, and the sand entered into the mold box through said plate. After this operation is completed, the mold box is turned over to the position shown in Fig. 1, being held therein by a movable locking pin 41, and then swung to position directly above the table 25, which is in its lower position. The clamping ring 31 has been

removed so that the ball 23 and connected table 25 are free to oscillate about a vertical axis. The handle 12 is then grasped and forced downwardly, latch bar 13 riding over the teeth 17 and post 18 and the table 25 being moved upwardly until the table engages against the under side of the plate 40. As the table is free to move, its upper side conforms to the under side of the plate automatically, as is obvious. When in firm contact with the plate 40, handle 34 is operated to clamp the ball 23 against movement, thereupon fixing the table 25 against movement. The plate 40 is then released from the box 37, handle 12 again grasped, the latch 13 drawn from the teeth 17, and the post 18 and table 25 lowered, drawing the mold carried on the plate from the box. Of course, with the type of mold shown, in which piston cores, such as indicated at 42 are formed from green sand, a specially constructed mold or core box is necessary, and one has to have certain operations performed therewith before the mold is free to be withdrawn, which operations are performed prior to lowering the table. This, however, is no part of the present invention, the special construction of the box being subject matter for a still further application for patent Serial Number 443,738, filed Feb. 10, 1921. After lowering the post 18 and attached table 25, the box 37 is swung out of the way and the plate 40 and mold carried thereby removed from the table, it being many times advisable to release the clamping means at 4 so as to swing the table to proper position so that the plate and mold may be taken direct from the table to a truck or gravity conveyor for transportation of the mold to any desired place in the foundry, so as to receive the cover or cope to complete the mold, and then to the pouring floor. It is evident that the mold shown in Fig. 1 for the production of pistons forms the drag of a completed mold, adapted to have a cope placed thereover. After removal of the plate 40 and mold thereon, the table is swung back to its original operative position, the clamping ring 31 released, and is thus ready for a repetition of the operation for a succeeding mold.

The automatic conforming of the table 25 to the plate 40 coupled with the simple and effective locking of the table against movement after such action renders the drawing of the mold downward sure and effective without danger of injury to the mold. The operation of the mechanism is simple, yet sure and the mechanism is of such construction that it is durable and has little or no chance to get out of order. The appended claims define the invention and all forms of structure coming within their scope are to be considered as comprehended by the invention.

I claim:

1. In combination, a support including a vertically positioned sleeve having a casing at one side thereof, a toothed disk rotatably mounted in the casing, an operating handle extending from the disk through a slot in the casing, interengaging means on the handle and casing for holding the handle in any position to which moved with respect to the casing, a post vertically mounted in the sleeve and provided with rack teeth at one side in mesh with the teeth of the disk, said post having a ball socket at its upper end, a ball seated in the socket, a short post projecting upwardly from the ball, a table connected with the upper end of said short post, a cap provided with an inclined cam under side attached to the upper end of the first post over the ball, said short post passing through the upper side of the cap, a clamping ring located between the upper side of the cap and the upper portion of the ball, said ring having an inclined cam upper side and a concaved recessed lower side fitting the ball, and a handle attached to the ring and passing through a slot in the side of the cap for turning the ring whereby the table may be clamped in fixed relation to the first post, or freed for oscillatory movement about the vertical axis of said post, substantially as described.

2. In combination, a support including a vertically positioned sleeve, a post mounted vertically therein, means to raise or lower said post, said post at its upper end having a ball socket, a ball seated in the socket, a short post projecting upwardly therefrom, a table attached to the upper end of said short post, and releasable means for clamping the ball against movement with respect to the first post, substantially as described.

3. In combination, a vertical supporting post, a sleeve rotatably mounted thereon, an arm projecting from the sleeve and terminating at its free end in a second sleeve, means for releasably clamping the first sleeve to the post, a second post mounted vertically in the second sleeve, means for raising and lowering said second post, means for releasably holding said second post against downward movement, a table mounted for limited universal movement at the upper end of the post, and means to releasably lock the table in fixed relation to said second post, substantially as described.

4. In combination, a vertical supporting post, a sleeve mounted thereon, an arm projecting from the sleeve, a second post mounted for vertical movements at the free end of the arm, means for raising and lowering said second post, means for releasably holding said second post against downward movement, a table mounted above the upper end of the second post for limited universal

movement, and means to releasably lock the table in fixed relation to the second post, substantially as described.

5. In combination, a vertical post, a sleeve mounted thereon, an arm projecting from the sleeve, a second post mounted vertically at the free end of the arm, means for raising and lowering said second post, means for releasably holding said second post against downward movement, a second sleeve rotatably mounted on the first post above the first sleeve, a forked arm projecting from the second sleeve, a mold box carried at the outer ends of said forked arm, a table mounted at the upper end of the second post for limited universal movement, said table being adapted to come against the under side of the mold box on upward movement of the second post automatically conforming to said under side of the mold box, and means to lock the table in fixed relation to said second post after conforming to the under side of the mold box, said locking means being manually operable and releasable at will, substantially as described.

6. In combination, a support including a vertically positioned sleeve, a post mounted vertically therein, means to raise and lower the post, means to releasably hold the post against downward movement, a ball socket formed at the upper end of the post, a ball seated in said socket and provided with an upwardly projecting short post, a table attached to the upper end of said short post, a cap attached to the upper end of the post over said ball, and manually operable means between the cap and ball and operatively engaging the same to releasably lock the ball against movement with respect to the post, substantially as described.

7. In combination, a post mounted vertically therein, means to raise and lower the post, means to releasably hold the post against downward movement, a ball socket formed at the upper end of the post, a ball seated in the socket, a short post projecting upwardly from the ball, a table attached at the upper end of said short post, a cap attached to the upper end of the post over the ball, the short post passing through an opening in the upper side of the cap, a ring shaped to engage against the upper portion of the ball around said short post, and a handle attached to the ring and extending outwardly through a side of the cap, said cap having a slot in its side for the passage of the handle, and said ring on its upper side and the cap at its adjacent portion being formed with cooperating cam surfaces whereby the ring may be tightened against the ball on rotative movement of the ring in one direction and released therefrom on rotative movement in the opposite direction, substantially as described.

8. In combination, a support including a

130

vertical sleeve having a casing at one side thereof formed with a vertical slot in its outer side, a disk rotatably mounted to turn about a horizontal axis within the casing, 5 said disk having gear teeth cut therein at its inner side, a handle attached to the disk and extending through said slot in the casing, a latch bar movably mounted on the handle, a series of ratchet teeth on the casing at one 10 side of the slot with which said latch bar is adapted to engage, a post vertically positioned in the sleeve and having a series of rack teeth at one side in mesh with the teeth on the disk, a table mounted on and

above the upper end of the post for limited 15 universal movement with respect to the axis of the post, and means to releasably lock the table against movement with respect to the post.

9. A construction containing the elements 20 in combination defined in claim 8, combined with a vertical key on the inner side of the sleeve, said post having a vertical key way therein in which said key is located, substantially as described. 25

In testimony whereof I affix my signature.

DONALD J. CAMPBELL.
